UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed February 19, 1923. Serial No. 619,839.

My invention relates to mining machines.

It has for its object to provide an improved mining machine. A further object of my invention is to provide such a machine of improved and very compact construction especially adapted to use in low vein work. A still further object of my invention is to provide an improved machine which is without change adapted to operate 10 as an over or under cutter. Further and more specific objects of my invention include the provision of an improved motor and motor supply and control mechanism, improved flexible feeding mechanism, improved cutting mechanism, and improved transmission mechanism between said flexible feeding and cutting mechanisms and said motor including improved controlling mechanism. These and other objects and 15 advantages of my improvement will, however, hereinafter more fully appear.

In the accompanying drawings I have shown for purposes of illustration one embodiment which my invention may assume 20 in practice.

In these drawings.

Fig. 1 is a plan view of a machine constructed in accordance with this embodiment of my invention, the cutter bar being illustrated in different positions.

Fig. 2 is a side elevation of the machine shown in Fig. 1, a part of the frame being broken away to facilitate illustration.

Fig. 3 is an enlarged plan view partially 35 in section of the cutter bar carrying end of the machine.

Fig. 4 is a longitudinal sectional view on line 4—4 of Fig. 3.

Fig. 5 is a transverse sectional view on 40 line 5—5 of Fig. 3.

Fig. 6 is a detail sectional view on line 6—6 of Fig. 4, showing the bar locking mechanism.

Fig. 7 is an enlarged horizontal sectional view of the motor and its supply connections.

Fig. 8 is a longitudinal sectional view on lines 8—8 of Fig. 7.

Fig. 9 is a transverse sectional view on 50 line 9—9 of Fig. 7.

Fig. 10 is an enlarged detail view of the oiler mechanism.

Fig. 11 is an enlarged longitudinal sectional view of the feeding mechanism on 55 line 11—11 of Fig. 1.

Fig. 12 is a transverse sectional view on line 12—12 of Fig. 11, showing the reverse gear.

Fig. 13 is a similar transverse sectional view on line 13—13 of Fig. 11, showing the 60 friction controlling mechanism.

Fig. 14 is a longitudinal sectional view partially in elevation on line 14—14 of Fig. 13 showing the feed controlling mechanism.

Fig. 15 is an enlarged end elevation of 65 the feeding end of the machine.

Fig. 16 is a diagrammatic plan view showing the machine adapted to make a longwall cut in one direction, the bar swinging arrangement of the parts being shown in 70 dotted lines.

Fig. 17 is a similar view showing the machine adapted to make a longwall cut in the opposite direction on a similarly located face.

75

Fig. 18 is a similar view showing the machine adapted to cut in one direction on an oppositely located face.

Fig. 19 shows the machine arranged for 80 a reverse feed along a face.

Fig. 20 is a similar view showing the machine arranged for fast feed about the mine.

Fig. 21 is a side elevation of the machine shown in Fig. 2 when adapted to operate 85 on a skid.

Fig. 22 is a similar view showing the machine of Fig. 2 adapted to operate as a top cutter.

Fig. 23 is a diagrammatic plan view showing one method of operating the machine to 90 make a cut extending a rib.

Fig. 24 is a similar view showing another method of operating the machine to make a similar cut.

Fig. 25 is a similar view showing the machine operating as a room and pillar machine in a heading.

In this illustrative construction I have 100 shown my invention applied to an air-propelled flexibly fed mining machine of the longwall type adapted to slide on its bottom 1 on a mine bottom and carrying on one end a pivoted cutter bar 2, the construction being such that after the cutter bar has been 105 inserted under the face, the frame portion of the machine, generally indicated at 3, may be disposed substantially at right angles to the cutter bar and moved longitudinally along the face and relative to flexible feed- 110

ing means of any suitable form, herein including a flexible feeding member 4 likewise disposed along the face and operatively connected to the opposite end of the machine 5 from the cutter bar.

Referring more particularly to the machine, it will be noted that the same herein comprises three sections, i. e. a motor section 5, a feed section 6, and a cutter carrying section 7, the feed and cutter mechanism carrying sections being herein disposed at opposite ends of the motor section and rigidly connected to the latter at points above the bottoms of the sections, as by a series of 10 bolt connections 8 preferably disposed in side pockets in the sections 5 and 6 as illustrated in Fig. 2, in such manner as to form a rigid exceedingly low frame slideable on the mine bottom. More particularly it will 15 be noted that herein the upper and lower surfaces of the three sections 5, 6, and 7 are, as preferably, disposed in the same plane in such manner as to unite to form a single shoe adapted to permit free movement of the 20 machine thereon over the mine bottom.

Referring more in detail to the motor section 5 and accordingly to Figs. 7, 8, 9, 10, it will be noted that this section has suitably journaled therein a fluid pressure 25 motor of the general character described and claimed in my copending application which has now matured into Patent No. 1,520,242, granted Dec. 15, 1924, and comprising a pair of longitudinally extending double helical rotors 9, 10 preferably meshing as herein on the longitudinal center line of the machine and housed in suitable intersecting bores 11, 12 formed in the section 5; the rotors 9, 10 each preferably having between 30 their oppositely disposed sets of helical teeth, a spur gear 13 meshing with its fellow. More particularly it will be observed that each of these rotors comprises a plurality of 35 oppositely disposed helical portions 14 on opposite sides of a spur gear and that these elements are clamped together by a plurality of bolts 15 carrying on their ends clamping rings 16 engaging opposite shoulders 17 on a shaft 18 to which one of the 40 helical tooth sections is keyed as at 19. In this connection attention is directed to the fact that as viewed in Fig. 7 the right hand helical section of one rotor is keyed to one shaft while the left hand section of the 45 other rotor is keyed to the other shaft, in such manner as to enable identical rotors to be utilized on the two shafts, the rotors being simply oppositely mounted on the different shafts. It will further be noted that 50 the shafts 18 have reduced portions adjacent their shoulders 17 which in turn are supported in motor head members 20, 21 seated in the opposite ends of the casing and herein having flanges 22 adapted to position the 55 same relative to the casing, suitable ball

bearings 23 preferably being provided between further reduced portions 24 on the shaft and the heads.

Operatively associated with the rotors above described is improved means for supplying pressure fluid thereto and exhausting the same therefrom. In a preferred form, a pressure fluid supply pipe 25, preferably having a suitable throttle therein (not shown), is suitably connected through a 60 usual strainer 26 with a removable supply connection 27 rigidly connected to 28, 29 to one side of the cutter carrying portion 7. Herein this connection is adapted to fit around the curved front head on the portion 80 7 and includes an elongated passage 30 communicating through a suitably bushed or packed opening 31 with a chamber 32 formed in the section 7. This chamber 32 in turn communicates with a longitudinally 85 extending passage 33 passing through the head 21 through suitable packed joints and extending longitudinally of the center line of the section 5 beneath the mesh line of the rotors 9 and 10, to a point below the spur 90 gear sections 13 where it communicates with a plain upwardly extending motor inlet 34, thus supplying motive fluid to the rotors in such manner as to cause the same and their 95 shafts to rotate in a well known manner in the opposite directions indicated by the arrows in Fig. 9. As shown herein, the exhaust from the rotors passes out of the opposite ends thereof into end exhaust chambers 100 35 communicating through baffle chambers 36 with outlets 37 disposed two in a set vertically at the opposite ends of each side of the motor section 5, the baffles serving to prevent the entry of foreign matter such as coal into the rotor casing when the rotors draw a vacuum in the casing as the motor is shut down. Here attention is also directed to the fact that a longitudinal passageway 105 38 is provided above the mesh line of the rotors connecting the two end exhaust 110 chambers.

In my improved construction the pressure fluid supply connections for the motor are made reversible. It will be noted that the pressure fluid supply connections are made to that side of the machine which is remote from the face during the making of the long-wall cut and provision is made whereby these connections may be changed from one side to the other as may be desirable when the machine is to cut in opposite directions along the face. To make this possible the section 7 is provided with a plurality of 115 passages 31 while the chamber 32 is branched and communicates with the passages 31 on opposite sides of the machine so that the connections 25, 26, 27, 28, 29 and 30 may be disposed at either side of the machine as may be desired. Here it will 120 also be noted that a cover plate 39 is at- 125 30

tached by screws 40 over the unused passage 31 through which the passage 30 would communicate with the unused chamber 32, and understood that the section 7 is also suitably 5 drilled to receive the bolts 28, 29 when the section 27 is reversely disposed. It will also be understood that both branches of the chamber 32 communicate with the passage 33 and consequently with the motor.

10 Here attention is also directed to the controlling mechanism for the fluid pressure supply which is preferably provided in addition to the usual valved supply connection 25. More particularly, it will be observed 15 that a hollow tubular throttle valve 41 having a longitudinally extending slot or aperture 42 therein is journaled in the passage 33 immediately beneath the motor inlet 34, this throttle valve 41 being rotatable on a 20 horizontal axis in such manner that rotation of the same acts to throttle more or less as desired the supply of pressure fluid from the passage 33 to the motor inlet 34. More 25 particularly, it will be noted that this valve 41 which is preferably so constructed as to be expanded by the fluid pressure in such manner as to resist a turning movement, is provided with a rod 43 extending in the opposite direction from the passage 33 and 30 through the head 20, and that this rod is journaled in the bottom of the section 5 and the head 20 and carries on a protruding end a pinion 44 meshing with teeth on a transversely disposed rack member 45 keyed at 35 46 to a transverse rod 47, likewise connected thereto by a set screw 48, the rod 47 in turn being mounted for transverse reciprocating movement when desired in suitable bearings in the section 6 and carrying a similarly 40 connected rack 49, see Fig. 13, on its opposite end meshing with the teeth of a pinion 50 on a longitudinally disposed shaft 51 which is in turn rotatable by a rotatable disc or hand wheel 52 on the end of the feed section 6.

Cooperating with the motor mechanism is also improved lubricating mechanism therefor. This mechanism herein comprises a plurality of lubricant chambers 53, 54, formed in the frame of the section 5 above the horizontal median plane thereof and a plurality of similar lubricant chambers 55, 56 below that plane. Herein one of these chambers 53 communicates with the bore for the rotor 9 through a small air passage 57 and also through a restricted oil discharge 58 located adjacent the bottom of the chamber and controlled by a valve 59 operatively connected, as through a pin 60, with an adjusting screw 61, in turn operable by an adjusting knob 62 disposed in a recess 63 in the side of the section 5 substantially midway between the top and bottom thereof. Thus it will be noted that the construction 65 is such that when the knob 62 is adjusted,

the air pressure passing from the rotor chamber into the chamber 53 and acting on the top of the oil therein forces the oil out through the aperture 58 and into the rotor chamber into the path of the pressure fluid 70 in such manner as to lubricate the rotor. Referring to the chamber 54, it will be noted that the same is not provided with a valve but that instead the opening in which the member 61 would be seated is plugged by 75 a plug 64 and that similar plugs close the chambers 55, 56, this arising from the fact that the chamber 54 is only used when that side of the machine is away from the coal face and therefore accessible, the plug 64 80 then closing the chamber 53, while the chambers 55, 56 are only used under like circumstances when the machine is turned bottom side up and operating with the top surface shown in Fig. 9 forming its shoe, all as 85 hereinafter more fully described. Here it will also be noted that these chambers may be filled through removable two part screened plug connections, 53', 54', 55' and 56' in both the top and bottom surfaces of 90 the machine.

Operatively connected to the motor hereinabove described is the cutting mechanism including the cutter bar 2. More particularly it will be noted that this cutting mechanism includes a cutter bit carrying cutter chain 65 circulated about the bar by a cutter chain sprocket 66 suitably driven by one or the other of the rotors 9, 10 as circumstances require. Referring more in detail to the driving connections, we will first consider the connections to the rotors. Here it will be observed that the shafts 18 of the rotors 9, 10 each have still further reduced ends 67 having keyed thereto identical but 100 reversely disposed long sleeved pinions 68, 69, of which the pinion 68 is disposed at the end of the reduced portion 67 on the shaft of the rotor 10 and held in position by keying and a suitable lock nut 70, while the 105 pinion 69, also held in place by keying and a suitable lock nut 71, is fixed to the shaft of the rotor 9 and disposed thereon closely adjacent the bearing 23, the two pinions 68, 69 thus rotating in parallel but longitudinally spaced transverse planes. Selectively cooperating with these pinions 68, 69 is an adjustable pinion 72 splined on a longitudinally extending shaft 73 disposed 110 between the rotor shafts, and suitably journaled on the head 21 in a ball bearing 74 and at its front end on a frame member 75 on the section 7 in a ball bearing 76. As illustrated, this pinion 72 also has a 115 clutch shipper ring 77 formed thereon and adapted to be engaged by a horizontally disposed U-shaped clutch shipper 78 pivoted on a vertical axis at 79 on the section 7 and having a worm gear sector 80, partially surrounding its pivot, adapted to mesh with a 120 125 130

worm 81 on a transverse shaft 82 journaled on the section 7 and extending above the shaft 73 when the parts are disposed as shown in Fig. 4. As illustrated, the shaft 32 is journaled in a suitable collar 83 threaded in the side of the section 7 and has keyed on its end a suitable knob 84 enabling it to be rotated at will, suitable provision, as by elongating the opposite end of the shaft 10 at 85, being made so that this knob may be transposed to the opposite side of the machine to permit suitable access and operation whatever side of the machine is adjacent the face. Thus, it will be observed that depending upon the adjustment of the shipper 78, the pinion 72 and consequently the shaft 73 may be rotated from different rotors and in opposite directions without reversing the motor.

Referring next to the operative connections between the shaft 73 and the cutter chain sprocket 66, it will be noted that the shaft 73 carries adjacent its bearing 76 a bevel pinion 86 underlying and meshing with a larger horizontally disposed bevel gear 87 having an elongated upwardly extending sleeve and journaled in suitable bearings 88, 89 between the frame portion 75 of the section 7 and a removable cover plate 90. This sleeve carries above the gear 87 a spur pinion 91 which meshes with a larger horizontally disposed spur gear 92 having a depending sleeve journaled on vertically spaced roller bearings 93, 94 which in turn surround a central vertical stud 95. This stud as shown is pinned to the cover plate 90 to prevent rotation of the stud and is also provided with reduced threaded portions 96, 97 on its ends threaded into small removable plates 98, 99 respectively attached by screws 100, 101 to the cover plate 90 and a bottom plate or shoe 102 forming a rigid continuation of the bottom of the machine and attached to the frame member 75. As illustrated, the depending sleeve on the gear 92 is connected through a semi-permanent clutch connection 103 with the upper end of a similar sleeve 104 on the sprocket 66, the ends of the sleeve 104 being similarly journaled on axially spaced ball bearings 105, 106 surrounding the lower end of its stud and the bearings 105 being spaced from and located relative to the bearings 94 by a flange 105' on the stud. Moreover, the sleeve on the gear 92 and the upper portion of the sleeve 104 are enclosed within an outside sleeve member 107 fixed to the frame by screws as at 108, while a complementary cup or thrust bearing member 109 seated in the aperture for the plate 99 and to which the lower end of the stud is also pinned, receives the lower end of the sleeve 104. Thus it will be noted that rotation imparted to the shaft 73 acts through the vertically compact reducing gearing de-

scribed to rotate the sprocket 66 to give the desired speed for the cutter chain.

Here it should also be observed that by reason of the cover plate 90 and the construction hereinabove described, it is made possible for the sprocket and sprocket bearings to be removed when desired and for the cutter bar 2 to be withdrawn. More particularly it will be noted that upon removal of the cover plate 90 it is possible to lift out the gear 92 with its bearings, remove the member 107, remove the plate 99, and drive out the stud 93 in such manner as to permit raising of the cup bearing 109 and sprocket 66 sufficiently to cause the bearing 109 to clear its seat and consequently permit longitudinal withdrawal of the bar 2, sprocket 66, and cup bearing 109 as a unit and subsequent ready separation of the same whenever desired. It will also be noted that suitable felt rings 110, 111 are inserted between the adjacent ends of the members 107, 109 and the sleeve 104 on the sprocket to exclude dirt and the like from the inner bearings. Here attention is directed to the fact that a member 112 fixed to and forming a journal for the bar 2 is journaled on the lower end of the sleeve 107 above the sprocket 66 and that a similar member 113 integral with the bar 2 is journaled on the member 109 below the sprocket, suitable bearing sleeves 114 and 115 being keyed within the members 112, 113 and permitting free swinging of the bar.

In my improved construction it will also be noted that improved means are provided for holding the cutter bar in different positions of adjustment about its pivot on the members 107 and 109. As shown herein the member 112 is formed in a separate piece 116 from the member 113 which is integral with the bar and the member 116 is attached by one or more screws 117 at points at one side of the sprocket axis in such manner as to produce a strong but readily separable construction. Moreover, it will be noted that the piece 116 which carries the member 112 is provided with a vertical bore 118 in an upstanding boss 119 grooved to overlie and if necessary to be supported on the edge of the head to maintain the bar in the desired plane of swing, and that a rotatable locking pin 120 is seated in this bore and provided with a removable flange 121 on its lower end seated in a larger bored-out portion 122 in the bar 2 in such manner as to prevent longitudinal separation of the pin 120 in the inverted positions of the machine, while permitting free rotation thereof. Herein it will also be noted that the pin is slotted transversely intermediate its ends in such manner as to form a locking portion 123 having a concave face and adapted to be received in any one of a plurality of corresponding cut-away portions 124 on the front

edge of the head when the pin is suitably turned, these cut-away portions 124 herein being so disposed on the head as to enable the bar to be locked in longitudinal and 5 opposite lateral positions. Moreover it will be noted that the pin 120 carries on its upper end an eccentrically disposed pin 125 adapted to receive one end of a curved double ended hook 126 adapted to be connected to 10 either end of the flexible feed member 4, the construction being such that a pull upon the latter and the eccentrically located pin 125 will rotate the portion 123 of the pin 120 into or out of operative engagement with 15 any one of the recesses 124 when it reaches the same and thus automatically lock the bar when the latter is turned to the right or left, the desired pull herein being obtained by operation of the feeding means herein- 20 after described. Attention is also directed to the hook 126 which it will be noted is of such length as to hold up the end of the feed chain 4 and thus prevent the same from being entangled in the cutter chain should the 25 feed chain break or a jack give way, the length of the hook and its connection to the pin being such that in either disposition thereof the end of the feed chain connected thereto is maintained at the necessary distance 30 away from the cutter bar to insure freedom from conflict. Referring more particularly to the hook it will also be noted that the same is provided with an elongated slotted end 127 enabling the desired freedom 35 of movement of the hook relative to the head and to the pin 120 as the bar is swung about the head. While referring to this mechanism, it should also be observed that the boss 119 is provided with a rounded 40 surface adapted to form a curved rubbing face engageable with the coal face to protect the mechanism from injury.

Having thus considered the cutter bar carrying end of the machine carried on the 45 section 7, we will now refer to the feeding mechanism carried on the section 6 and co-operating with the flexible feeding means 4, the latter herein assuming the form of a feed chain. In my present construction 50 these means include fast and slow feeding mechanism adapted to rotate a feed operating member 128, hereinafter more fully described, engageable with the feed chain 4 and herein disposed on the end of the section 55 6 on a horizontal axis extending longitudinally of the machine. Referring more particularly to this feeding mechanism including the driving connections between the motor and the feed operating member, we 60 will first consider the fast feed ordinarily used in moving the machine about the mine and swinging the bar when not cutting, although it should be understood that this fast feeding mechanism and more particularly 65 my improved mechanism may be used dur-

ing cutting when cutting conditions are favorable.

Considering this fast feed mechanism more specifically, it will be noted that the opposite end of the rotor 9 from that previously considered in connection with the drive for the cutting mechanism, is provided with a reduced portion 129 shorter than its opposite reduced portion 67 and having keyed thereto and suitably attached 70 thereto by a lock nut 130, a pinion 131 which meshes with a larger spur gear 132 suitably carried in a chamber 133 formed in the head 20 and journaled in suitable ball bearings 134 carried on the head. This gear 132 75 is in turn rigidly connected as by keying to a driving pinion 136 disposed coaxially therewith and outside the head and held in assembled relation to the bearings 134 by a bolt connection 135, which pinion in turn 80 meshes with a spur gear 137 keyed to a short longitudinally disposed shaft 138 journaled in suitable bearings 139 carried by a ring section 140 receivable in a corresponding longitudinally disposed and centrally located bore 141 extending throughout the length of the section 6. This ring section 140 is adapted to be inserted or removed longitudinally from the rear end of the section 6 and, as herein, preferably has a 85 cut-away portion 142 to permit free rotation of the gear 137, a web portion 143 in which one of the bearings 139 is carried, and a hub portion 144 in which a bearing 145 for one end of a longitudinally disposed 90 horizontal main feed driving shaft 146 is journaled. As shown the shaft 138 and gear 137 are suitably located relative to the bearings 139 by suitable bearing rings 147 and the shaft has one end protruding from 95 one bearing and carrying a pinion 148 thereon which in turn meshes with a larger internal gear 149, the pinion and bearing being held in assembled relation by a bolt connection 100 of the same type as the bolt connection 135. The hub 150 of this gear is herein journaled on a suitable bearing sleeve 151 on a sleeved clutch member 152 keyed to the shaft 146 and both are spaced from the bearing 145 by a sleeve 151'. Herein, it will 105 also be noted that the member 152 carries a series of friction discs 153, surrounding the member 152 and disposed within a sleeve on the internal gear 149, which cooperate with a corresponding series of friction discs 154 110 carried by the sleeve on the internal gear. As shown, the sleeve on the internal gear is also provided with a plurality of radially located longitudinally extending apertures 155 receiving radial fingers or extensions 156 115 on an interlocking member 157 keyed to a pinion 158 which is in turn freely rotatable on the shaft 146, while between these fingers 156, friction clutch operating fingers 159, carried on a disc 160 disposed coaxially with 120

130

the hub of the member 157, extend longitudinally into contact with one set of friction discs. As shown the opposite end of the shaft 146 is also journaled in a suitable ball bearing 161 carried in the hub 162 of a ring section 163, similar to the section 140, and a pinion 164, like the pinion 158, is keyed to the shaft at a point adjacent the bearing 161. This pinion in turn meshes with a gear 165, identical with the gear 137, keyed to a short longitudinally extending shaft 166 identical with the shaft 138 and likewise journaled in identical bearings 167, in this instance carried by the section 163 and provided with identical spacing washers 168 between the pinion and the bearings. This shaft 166 also carries on a protruding end a pinion 169, identical with the pinion 148, meshing with an internal gear 170, of the same size and number of teeth as the gear 149, disposed coaxially with the shaft and on the opposite side of the web of the ring section 163. This internal gear 170 is in turn keyed to an enlarged portion on a short longitudinally extending shaft 171 extending coaxially with the shaft 146 and through the feed operating member 128. Thus it will be noted that the rotation of the rotor 9 will be transmitted through the pinion 131, gear 132, pinion 136, gear 137, pinion 148, internal gear 149, friction clutch 153, 154, clutch member 152, and shaft 146 to the pinion 164, gear 165, pinion 169, internal gear 170, and shaft 171 to the feed operating member 128 to rotate the latter at a predetermined high or fast feed speed whenever the clutch controlling member 160 is operated to connect the clutch. It will here further be evident that the speed of feed may be lowered at will by slipping the friction discs 153, 154.

Here it will also be noted that the member 128 is provided with a reduced portion 172 on one end journaled on a suitable bearing ring 173 carried in a correspondingly shaped opening in a vertically disposed portion or boss 174 on a frame section 175 forming a rear head for section 6 and set in the end of the bore, and having in its head a similar coaxially disposed opening carrying a bearing sleeve 176 in which a reduced inner end of the member 128 is journaled. In order to provide for adjustment of the shaft 171, it will also be noted that the end of the member 128 is recessed as shown at 177 to receive a correspondingly shaped clamping member 178 having a flange 179 extending radially over the boss 174, while a screw 180 is extended through this member 178 and threaded into the end of the shaft 171, the opposite end of which carries a collar 181 abutting against the inner surface of the hub of the internal gear 170.

Next referring to the slow or cutting feed, it will be noted that when the clutch operat-

ing member 160 is in inoperative position and the clutch is released, power will still be supplied to the interlocking member 157 through the pinion 158 which is freely rotatable on the then stationary shaft 146. This pinion in turn meshes with a pinion 182 carried on a shaft 183 similar in all respects including its bearings, to the shafts 138 and 166 and like the shaft 166 preferably disposed on the opposite side of the shaft 146 from the shaft 138. Here it will be noted, however, that this shaft 183 is journaled in another ring section 184 similar to the ring sections 140 and 163 and likewise carried in the bore 141, but in this case spaced from the ring section 141 by an intermediate more thin ring section or spacing section 185. In this instance also it will be noted that the hub of the ring section carries a roller bearing 186 for the shaft 146 and that the shaft 183 carries a pinion 187 meshing with an internal gear 188 which is suitably spaced from the bearing 186 by a ring 189 located in the same general relation as the ring 151 described in connection with the internal gear 149. This internal gear 188 is in turn keyed to the sleeve of a pinion 190, corresponding to the pinion 158, and this pinion in this instance meshes with a larger reverse gear 191, see Fig. 12, journaled on a supplementary stub shaft 192, in general similar to the shaft 183 but not shown in detail. Thus the rotation of the pinion 190 may be transmitted through the gear 191 to rotate a gear 193 meshing with the gear 191 and carried on a shaft 194, similar in all respects to the shaft 183, in such manner as to cause the gear 193 to rotate in a reverse direction and accordingly cause the shaft 194 to rotate in the same direction and impart a similar direction of rotation to its pinion 195 and another internal gear 196, identical with the gear 149. Here it will be noted that these parts are carried in still another ring section 197, similar to the sections 163, 184, 140 previously described, and likewise carrying a ball bearing 198 for the shaft 146, the hub of the internal gear being spaced from the bearing by a ring 199. This internal gear 196 also houses a friction clutch, generally identical with the construction previously described in connection with the clutch 153, 154, and including clutch elements 200, 201, one of which is carried on a clutch member 203 keyed to the shaft 146, an intermediate member 204 keyed to the sleeve on the pinion 164, and a clutch operating member 205 surrounding the hub of the interlocking member, although in this instance the member 204 has no interlocking function and is only a spacing and disc retaining member. Here attention is also directed to the fact that between the ring section 197 and the ring section 163 a second spacing ring 206, similar in all respects to the spacing ring 185, is pro-

vided and here attention is directed to the fact that all of these rings and ring sections are suitably keyed in the bore 141 as at 207 in such manner as to prevent rotation of the 5 same in the bore. As a result of the mechanism above described, it will be evident that although the clutch 153, 154 is disconnected, rotation will constantly be imparted through the pinion 158, gear 182, pinion 187, internal 10 gear 188, pinion 190, gear 191, gear 193, pinion 195, and internal gear 196 so that whenever the clutch 200, 201 is connected, the pinion 164 will be rotated at a slow or cutting speed in the opposite direction from the fast 15 speed previously described in such manner as to convey through the gear 165, pinion 169, internal gear 170, and shaft 171 a similar predetermined slow or cutting speed of rotation to the feed operating member 128. 20 Here it will also be evident that by slipping the friction, this speed may also be reduced when desired.

Operatively associated with the feeding mechanism above described is also improved 25 controlling mechanism shown more particularly in Figs. 13 and 14, wherein it will be observed that a clutch shipper 208 of U-form and extending around the shaft 146 is journaled in lugs on the ring section 185 and 30 provided with rollers 209 adapted to engage the disc-like outer surface of the clutch operating member 160. Moreover, it will be noted that this clutch shipper is provided with a tail or extension 210 extending out 35 through a lateral aperture 211 in the ring 184 into a corresponding chamber 212 formed in the frame section 6 and is there provided with U-shaped arms 213 operatively connected to a non-rotatable nut 214. 40 This nut is herein movable longitudinally relative to a threaded portion 215 on a rotatable shipper rod 216 when the latter is rotated in a suitable bearing 217 for the end thereof bolted on the ring 185. As shown, 45 this rod 216 has also an extension 218 seated in and keyed in the opposite end thereof and having its own outer end suitably journaled at 219 in a bearing sleeve which is in turn seated in a removable bearing member 220 50 carried in the head portion of the extension 175 which closes the end of the frame section 6. This rod section 218 in turn carries another threaded section 221 reversely threaded with respect to the section 215 and also 55 carrying a nut 222 cooperating with a clutch shipper mechanism, generally indicated at 223, similar in all respects to the clutch shipper mechanism previously described and carried by the ring section 185, but it will 60 be noted that this shipper mechanism is here carried by the ring section 206 and operates upon the clutch operating member 205 of the clutch 200, 201. As illustrated, a spur gear 224 is suitably fixed to the end of the 65 shaft 218 and meshes with a corresponding

gear 225 fixed to the end of a longitudinally disposed feed controlling shaft 226 extending beyond the end of the frame section 175 and operable by a feed controlling hand wheel 227. Thus it will be observed that 70 when this hand wheel 227 is turned in one direction, the clutch 153, 154 controlling the fast feed will be connected to produce a fast feed and the clutch 200, 201 simultaneously disconnected, while when the hand wheel is 75 turned in the opposite direction, the clutch 153, 154 will be disconnected and the clutch 200, 201 connected, to produce a slow feed in the opposite direction.

Operatively associated with the feed operating member 128 is also improved guiding means for the flexible feeding member 4. These means are herein disposed upon the frame extension 175 and preferably comprise a plurality of sets of guide sprockets 80 disposed on upright axes on opposite sides of the longitudinal center line of the machine and rotatable in horizontal planes. As shown herein, a guiding member 228 is mounted on a vertical axis closely adjacent the feed operating member 128 and as shown in Fig. 15 slightly below the axis thereof, the sprocket being disposed in such position that the feed chain passing off of the under side of the feed operating member 128 may 85 pass around the inner side of the guide 228. This guide is herein also held in position by a suitable screw 229 threaded into a vertical stud 230 keyed in an upstanding boss 231 on the bottom surface of the section 175, the screw 229 acting to clamp the stud in position relative to an upper boss 232 formed at one side of the boss 174 and being freely accessible from the end of the section 175. 90 A similar guide sprocket 233 is similarly mounted on the opposite side of the feed operating member 128 in the same general location. Also it will be noted that laterally of each of these members 228 and 233 and herein in transverse alinement therewith, external or corner guides 234 and 235 are similarly mounted, the same preferably extending slightly beyond the lateral edges of the machine frame as shown. Here attention is 95 also directed to the fact that the upper and lower extremities of the frame extension 175 are turned inward as shown at 236 to provide a proper shoe surface permitting free longitudinal movement of the machine whether operating as a top or bottom cutter, 100 and that, due to the arrangement and location of the feed operating and guiding elements and the open end of the section 175, access may be readily had to the feed and 105 guide elements to change the arrangement of the flexible feeding member 4 relative thereto as desired. Attention is also directed to the fact that the whole extension 175 is herein attached to the section 6 in such 110 manner as to seal the end thereof and there-

by enable the bore 141 to be filled as needed with lubricant while at the same time permitting the removal of the section 175 by means of the removal of readily accessible 5 screws 237 and the consequent possibility of withdrawing all of the various ring sections and spacing rings with the connected feed transmission mechanism carried thereby, including the shaft, from the then open end of 10 the section 6.

In the operation of my improved machine, it will be evident that by reason of my improved construction it is made possible to operate the machine with equal facility as a top or bottom cutter by simply turning the machine over, the frame being so constructed as to permit it to move with equal facility on its top or its bottom, while the cutting and feeding mechanisms and 20 even the lubricating arrangement are similarly adapted to this dual service. More particularly it will be observed that when the machine is disposed as shown in Fig. 2 it is adapted to use as a bottom cutter whereas when the same is turned over and disposed as shown in Fig. 22, it is adapted to use as a top cutter, while when mounted on a vertically adjustable skid 238, it may be either an intermediate or top cutter as desired. Moreover, it will be observed that in any relation the flexible feeding means are adapted to cooperate as preferred in the same plane as the cutter bar, and that in either position of the machine it is possible 35 for the flexible feeding means to be so arranged as to swing the bar in the desired direction to insert it by a suitable movement under the coal and then to move the machine bodily longitudinally along the coal face. More specifically considering these 40 positions, it will be noted that with the bar unlocked in a longitudinal or transport position, the end of the chain 4 is connected to the hook 126 in the manner indicated in Fig. 16 by extending the chain from the 45 feed operating member 128 along the inner side of the guide sprocket 233, outward around the outer side of the guide sprockets 233, 228 and 234, and then longitudinally 50 along the machine to the hook. Thus a pull upon the chain at a feeding speed, produced by a suitable operation of the hand wheel 227 to connect the clutch 153, 154, causes the bar to be swung from its longitudinal 55 position indicated in dotted lines in Fig. 16 to the full line position illustrated in that figure in which, by reason of the movement of the portion 123 of the pin into the recess 124, the bar will be automatically locked. After the bar has been thus adjusted 60 the chain is then disconnected from the hook and connected as shown in full lines in Fig. 16, the same then only being reversed relative to the member 234 and then disposed laterally in advance of the machine to

a fixed abutment, whereupon, by similarly operating the hand wheel 227, the machine will move along the face at a slow or cutting speed. If on the other hand it is desired for the machine to cut in the opposite 70 direction relative to the same face, it will be evident that by rearranging the parts as shown in Fig. 17 the same results may be obtained, the chain being extended along the inner surface of 233 and the outer surface 75 of 235 to swing the bar, and along the inner surfaces of 233 and 235 to anchor it for transverse cutting. Further, it will be evident that if it is desired to cut in an oppositely located face, the same results may be 80 obtained by arranging the parts reversely as shown in Fig. 18. Moreover, when it is desired for any reason to reverse the slow feed, this may be accomplished by re-arranging the feed chain relative to the guide 85 sprockets in such manner as without reversing the direction of rotation of the feed operating member 128 to obtain the reverse slow feed desired, this arrangement being illustrated in Fig. 19 and obviously being 90 the same as in Fig. 16, save that the machine is moving in the opposite direction. Attention is also here directed to Fig. 20 wherein it will be noted that the feeding means is extended longitudinally from one 95 of the guides 228, 233 as may be done when it is desired to move the machine at fast speed about the mine, the arrangement here being such that the pull is exerted nearer the longitudinal center line of the machine. Referring to Fig. 23 it will also be noted that where it is desired to extend a rib, it is possible when the bar is laterally disposed as shown, by extending the chain along the inner side of the guide 233 and the outer 100 side of 235 and along the machine to a fixed jack at the rib as shown, to draw the bar into the face to the sumped in position indicated in dotted lines, and thereafter, by disconnecting the chain from the jack and passing it around the outside of the guides 235, 105 233, and 228 and around the inside of the guide 234, then extent it laterally along the face to enable the machine to make the transverse cut, this without reversing the 110 motor and without requiring any swinging of the bar. In Fig. 24, it will also be noted that the rib may be extended by leaving the bar longitudinally disposed as shown in that figure and extending the chain along the 115 inner side of 233 and to the outer side of 235 to a jack at the rib, whereupon the bar may move longitudinally into the face and the machine frame then be swung laterally relative to the bar into its usual position 120 parallel to the face. In swinging the frame, the bar is first unlocked, preferably manually, and the free end of the chain extended along the inner side of 228 and the outer 125 side of 234 to a jack adjacent the face as in 130

dicated, whereupon by operating the fast feed the frame may be swung rapidly toward its dotted line position indicated at the left. When the bar and frame are disposed 5 in this transverse cutting position, the bar is then again locked in position and the chain then arranged as shown, the same extending around the member 233 and along the outer side thereof to the member 228 and 10 then along the inner side of the member 234 to the jack or abutment adjacent the face so that the machine may be fed along the chain at a slow or cutting feed. In Fig. 15, I have also shown the machine adapted 15 to use as a room and pillar machine extending a rib as in a heading. In this construction it will be noted that a swing arm or supplementary guide 239 of any usual form is suitably attached to the front head in any 20 usual manner. It will also be noted that the bar being left longitudinally disposed, the chain is extended during sumping along the inner surface of 233 and the outer surface of 235 to a jacket at the rib as in Fig. 25. After the sumping operation, the chain 25 is disconnected from the jack adjacent the rib and then extended along the inner surface of 233 and the outer surface of 233, 228, and 234, longitudinally along the frame and 30 then around the guide 239 to a laterally located jack adjacent the face, to effect lateral movement of the machine to extend the heading.

As a result of my improved construction 35 it will be observed that an exceedingly compact machine vertically is produced, my improved construction in fact enabling a machine having a total height of 12 inches to be produced, a far lower machine than has heretofore been thought possible, and one 40 which is accordingly adapted to use in even the lowest commercially workable veins. Further, by reason of the provision of a machine equally adapted to be operated on 45 its top or its bottom, it will be noted that while retaining this low characteristic, a machine is produced which is equally well adapted to use as an overcutter or undercutter depending upon the circumstances in 50 the particular mine. Moreover, attention is directed to the fact that by reason of the provision of improved supply connections and controlling mechanism adapted to be located upon opposite sides of the machine, 55 the latter is adapted to work along a face at either side of the machine without injury to the connections or inconvenience on the part of the operator or delays of the machine, the supply connections and controlling 60 mechanisms always being capable of being placed on the side of the machine away from the face. Attention is also directed to the fact that the control mechanism for the feed is exceedingly simple, involving only a single control member ca-

pable of being operated quickly and easily by an operator at his station at the advancing end of the machine frame where it will also be noted that the operating member for the motor throttling mechanism is likewise 70 conveniently located, these two controlling members being the only members which in ordinary operation along the face it is necessary for the operator to use. So far as the motor structure is concerned, it will also be 75 noted that by my improved construction it has been made possible materially to reduce the diameter and consequent cost of the motor while retaining the same of sufficient horsepower to operate the machine and otherwise specifically improving the motor. It will also be observed that by my improved arrangement of guiding means for the flexible feeding member it has been made 80 possible to eliminate the necessity for connection of the feeding mechanism to either rotor while still making available the desired variations of feed. As for the cutting mechanism, attention is here also directed to the fact that through my improved automatic locking means it is not only possible to automatically lock the cutter bar when moving in either direction in any position after a manual release and a proper connection of the feed chain, thereby saving 85 considerable time in this operation, but that it is also made possible to utilize as a part of this automatic mechanism, a hook which performs the dual function of a connecting and operating member for the locking 90 mechanism and of a safety sumping member preventing conflict between the feed and cutter chains. Moreover, it will be observed that at the same time that an exceedingly 95 low or flat cutter head construction is produced, the mechanism, by reason of my improved arrangement of parts including the supports for the cutter chain sprocket, is exceedingly strong and rugged. As for the feeding mechanism, by reason of the improved 100 arrangement of the same, it will be observed that it is not only possible to reduce the manufacturing cost by duplicating a large number of elements, but to enable the whole mechanism to be readily accessible 105 whenever desired, even in low coal, the spacing members with their connected parts and the shaft being removable longitudinally of the machine when the rear head section is removed. Attention is here also directed 110 to the fact that by my improved arrangement of feeding parts including the internal gears, it is made possible to compact the feeding mechanism vertically to a marked 115 degree and that at the same time that this is made possible, it is also made possible to provide large friction clutches of ample capacity well adapted to stand up under the most severe demands of service, the same if need be being capable of being even larger 120

than those shown. These and other advantages of my improved construction will, however, be clearly apparent to those skilled in the art.

5. While I have in this application specifically described one form which my invention may assume in practice, it will be understood that this form is shown for purposes of illustration and that the invention 10 may be modified and embodied in various other forms and certain features thereof applied to other than air propelled machines without departing from its spirit or the scope of the appended claims.

13. What I claim as new and desire to secure by Letters Patent is:

1. A mining machine comprising an invertible frame slidable over a mine bottom during cutting and cutting mechanism, said machine being operable during cutting in inverted positions to enable said cutting mechanism to operate in different planes and said frame having opposite surfaces each adapted to slidably engage the bottom and support 20 the machine during cutting and formed to permit free sliding of said machine upon the bottom.

2. A mining machine comprising an invertible cutter carrying frame and operable 30 during cutting when slidably supported on the mine bottom on opposite surfaces thereof to enable the machine to cut in different planes, said machine having lubricating means adapted to function with equal efficiency in inverted positions of the machine.

3. A mining machine comprising an invertible cutter carrying frame and operable during cutting when slidably supported on the mine bottom on opposite surfaces thereof to enable the machine to cut in different planes, said machine having feeding and cutting mechanism, and controlling means therefor, said controlling means arranged to 45 permit substantially equally facile manual operation in inverted positions of the machine.

4. A mining machine comprising an invertible cutter carrying frame and operable during cutting when slidably supported on the mine bottom on opposite surfaces thereof to enable the machine to cut in different planes, said machine having a motor and feeding mechanism, and controlling means therefor, said controlling means arranged to 50 permit substantially equally facile manual operation in inverted positions of the machine.

5. A mining machine comprising an invertible cutter carrying frame and operable 60 during cutting when slidably supported on the mine bottom on opposite surfaces thereof to enable the machine to cut in different planes, said machine having a motor and cutting mechanism, and controlling means therefor, said controlling means arranged to 65 permit substantially equally facile manual operation in inverted positions of the machine.

mit substantially equally facile manual operation in inverted positions of the machine.

6. A mining machine comprising a frame slidable over a mine bottom during cutting and cutting mechanism, said machine frame 70 having substantially coextensive opposite surfaces each constructed to support the machine when engaged with the mine bottom and each having an edge, adapted to constitute a leading edge during machine feeding, 75 upturned to facilitate sliding.

7. A mining machine comprising an invertible cutter carrying frame disposable on the mine bottom and having opposed surfaces each constructed to support the machine for sliding movement over the mine bottom to enable the machine to cut in different planes, said machine comprising mechanism 80 operable in either position thereof.

8. A mining machine comprising an invertible cutter carrying frame disposable on a mine bottom and having opposed surfaces each constructed to support the machine for sliding movement over the mine bottom to enable the machine to cut in different planes, 85 said machine comprising lubricating and controlling mechanism operable in either position thereof.

9. A mining machine comprising an invertible frame having opposed surfaces each 90 constructed to support the machine for sliding movement over the mine bottom, said machine comprising cutting mechanism operable to cut in different planes when said frame is slidably supported on different surfaces directly on the mine bottom.

10. A mining machine comprising an invertible cutter carrying frame and operable to cut with equal facility in different planes when slidably supported on opposite surfaces 105 directly on the mine bottom.

11. A mining machine operable in inverted relations relative to a mine bottom to enable the machine to cut in different planes and including flexible feeding mechanism operable in either direction and effective to slide said machine over the mine bottom while supported directly on the latter.

12. A mining machine operable in inverted relations relative to the mine bottom to enable the machine to cut in different planes including kerf cutting mechanism and flexible feeding mechanism operable in the plane of the latter in either relatively inverted position of the machine to feed the latter while slidably supported directly on the mine bottom.

13. A mining machine operable in inverted relations relative to a mine bottom to enable the machine to cut in different planes and including flexible feeding mechanism operable in either direction and effective to slide said machine over the mine bottom while directly supported on the latter, said feeding mechanism having controlling mechanism 125 130

disposed for equally facile manual control in either position of said machine.

14. A mining machine operable in inverted relations relative to a mine bottom to enable the machine to cut in different planes including kerf cutting mechanism and flexible feeding mechanism operable in the plane of the latter in either relatively inverted position of the machine for feeding the latter while 10 slidably supported directly on the mine bottom, said feeding mechanism having controlling mechanism disposed for equally facile manual control in either position of said machine.

15. In combination, a mining machine skid slidably engageable with the mine bottom, and a mining machine thereon including a frame generally rectangular in cross section and also including cutting mechanism and bodily invertible relative to said skid to bring opposite surfaces into engagement with the latter and to dispose said cutting mechanism in different planes, said machine having lubricating means and feeding 25 means adapted for effective operation in either position of said machine on said skid, said feeding means being adapted to feed said skid and machine over the mine bottom during the cutting operation.

16. A mining machine operative with its opposite sides selectively adjacent a face and including a pressure fluid motor, a supply chamber therefor, a throttle valve between said supply chamber and said motor, and pressure supply connections for the latter whereby pressure may be supplied thereto from opposite sides of the machine including a rigid detachable supply connection forming a part of the machine and extending to one end of said machine and disposable at either side thereof.

17. A mining machine operative with its opposite sides selectively adjacent a face and including a pressure fluid motor, a supply chamber therefor, and a single detachable power supply connection forming a part of the machine transposable to opposite sides of said machine and adapted to be secured thereto at either side thereof at longitudinally spaced points and in each position adapted to be connected to a power supply line.

18. A mining machine operative with its opposite sides selectively adjacent a face and having cutting mechanism, a pressure fluid driving motor therefor comprising intermeshing rotors, and means for selectively connecting said rotors to said mechanism including a plurality of operating connections on the opposite sides of said machine and adjacent said cutting mechanism.

19. A mining machine operative with its opposite sides selectively adjacent a face and having cutting mechanism, a pressure fluid driving motor therefor comprising inter-

meshing rotors, and means for selectively connecting said rotors to said mechanism including a plurality of operating connections on the opposite sides of said machine and adjacent said cutting mechanism and a trans- 70 posable operating member.

20. A pressure fluid operated mining machine operative with its opposite sides selectively adjacent a mine face and having a plurality of pressure fluid supply inlets on 75 opposite sides thereof, and means for utilizing a single pressure fluid supply connection including a transposable supply connection forming a part of the machine and detachably secured to the side thereof and having 80 a portion extending to one end of said machine and connectable thereto at said end and a cover for the unused inlet.

21. A mining machine having a swinging cutter chain carrying cutter bar and flexible 85 feeding means, and automatic bar locking means operable without manual intervention to lock said bar when a predetermined position of the latter is reached, said flexible means being connectible to effect bar 90 swing with said locking means and including means for preventing contact between said flexible means and said cutter chain when slack enters said flexible means while the latter extends above and across the path 95 of said cutter chain.

22. A mining machine having a swinging cutter chain carrying cutter bar and flexible feeding means, and automatic bar locking 100 means movable with said bar operable without manual intervention to lock said bar when a predetermined position of the latter is reached, said flexible means being connectible to effect bar swing with said locking means and including means for preventing 105 conflict between said flexible means and said cutter chain when slack enters said flexible means while the latter extends above and across the path of said cutter chain.

23. A mining machine having a swinging cutter chain carrying cutter bar and flexible feeding means, and automatic bar locking means arranged in the central longitudinal vertical plane of said bar operable without manual intervention to lock said bar when 110 a predetermined position of the latter is reached, said flexible means being connectible to effect bar swing with said locking means and including means for preventing 115 conflict between said flexible means and said cutter chain when slack enters said flexible means while the latter extends above and across the path of said cutter chain.

24. A mining machine having a swinging cutter chain carrying cutter bar and flexible 120 feeding means, and automatic bar locking means including an element rotatable on an axis perpendicular to the plane of the bar and operable without manual intervention to lock said bar when a predetermined position 125 130

of the latter is reached, said flexible means being connectible to effect bar swing with said locking means and including means for preventing conflict between said flexible means and said cutter chain when slack enters said flexible means while the latter extends above and across the path of said cutter chain.

25. In a mining machine, a frame, and cutting mechanism thereon including a cutter chain sprocket rotatably mounted thereon, a cutter bar movable about the sprocket axis as a pivot, and cutter bar journals carried on said bar and comprising bearing sleeves adapted to surround and cooperate with stationary bearing members and disposed on opposite sides of said sprocket at equal distances therefrom above and below the latter.

26. In a mining machine, a frame, and cutting mechanism thereon including a cutter chain sprocket rotatably mounted thereon, a cutter bar movable about the sprocket axis as a pivot, and cutter bar journals carried on said bar and comprising bearing sleeves adapted to surround and cooperate with stationary bearing members and disposed on opposite sides of said sprocket at equal distances from the median horizontal plane of said bar.

27. A mining machine including a frame, and cutting mechanism movable about a pivot thereon including a pivoted bar having a journal thereon and a removable bar member attached to said bar and carrying a cooperating journal, said journals being arranged at equal distances from the median horizontal plane of said bar.

28. A mining machine including a frame having on its exterior an arcuate portion extending to the sides thereof, and cutting mechanism thereon including a swinging bar pivoted thereon midway between the sides of said frame, said bar being swingable to either side of the machine and provided with axially spaced pivotal supporting means and an upstanding boss of short circumferential extent overlying and during swinging movement cooperating with said portion to maintain the bar in the desired plane of swing.

29. Mining machine cutting mechanism comprising a horizontal beveled gear, a spur pinion above and coaxial therewith, a larger spur gear meshing with said pinion, and a cutter chain driving sprocket below and rotatable with said larger gear, said cutter chain driving sprocket having a bearing therefor below the latter.

30. A mining machine cutting mechanism including a power driven gear, a coaxially disposed cutter chain driving sprocket rotatable therewith, a coaxially disposed stud extending through each of the same, anti-friction bearings between said gear and stud and said sprocket and stud spaced longitudi-

nally of the latter, and a cutter bar pivotally supported coaxially with said stud.

31. A mining machine cutting mechanism including a power driven gear, a coaxially disposed cutter chain sprocket, each of said elements having interengaging sleeves and said gear being axially removable, and a journal sleeve enclosing said sleeves and removable axially upon axial removal of said gear.

32. A cutting mechanism for mining machines including an axially removable gear, a coaxial stud, a coaxial cutter chain sprocket rotatable with said gear, bearings disposed coaxially with said stud, and a coaxial cup bearing for said sprocket.

33. In a mining machine, a frame having a cuttings passage, a cutter chain sprocket journaled in said passage, and bearing means for said sprocket including a plurality of members removable through a wall of said passage and a cup member carried on the bottom of said passage whereby upon removal of said plurality of members said sprocket may be removed longitudinally of said passage.

34. In a mining machine, a frame having means forming a cuttings passage and a chamber above the same, a sprocket journaled in said passage, a pivoted bar having journals coaxial with said sprocket, driving and bearing mechanism in said chamber removable axially of said sprocket to permit transverse withdrawal of said sprocket and bar, and means including a removable chamber-closing plate whereby said driving and bearing mechanism may be removed.

35. A mining machine comprising cutting and feeding mechanism, a motor operatively connected thereto comprising intermeshing rotors disposed in the same horizontal planes and having an upright inlet, and controlling mechanism operable from one end of said machine including a throttle valve disposed in said inlet.

36. A mining machine comprising cutting and feeding mechanism, and a driving motor including a casing, intermeshing rotors therein having shafts operatively connected to said mechanisms, and detachable heads disposed within the peripheries of the ends of said casing and on which said shafts are journaled, the adjacent ends of said shafts being journaled in one head.

37. A mining machine comprising cutting and feeding mechanism, and a pressure fluid motor operatively connected thereto including a casing having therein intermeshing rotors with their peripheries extending to points substantially equally closely adjacent the top and bottom of said casing, and exhaust passages from said rotors in the sides of said casing.

38. A mining machine comprising cutting mechanism, and driving mechanism therefor.

- including intermeshing rotors having parallel shafts, longitudinally spaced gears fixed to said shafts, a supplemental shaft connected to said cutting mechanism, and a gear 5 adjustable longitudinally of said supplemental shaft selectively engageable with said gears.
39. A mining machine comprising cutting and feeding mechanism and a pressure fluid 10 motor therebetween operatively connected thereto and including a casing having therein intermeshing rotors with their peripheries extending to points closely adjacent the top and bottom of said casing, end exhausts 15 for said rotors in the sides of said casing, and rotor lubricating means between said exhausts.
40. A mining machine having a frame selectively disposable with its opposite sides 20 adjacent a face, a pressure fluid motor therein comprising intermeshing rotors, and means comprising a plurality of lubricant chambers whereby lubricant may be supplied at will to said rotors from the side removed from the face.
41. A mining machine having a frame selectively disposable with its opposite sides 25 adjacent a face, a pressure fluid motor therein comprising intermeshing rotors, and means comprising a plurality of lubricant chambers whereby lubricant may be supplied at will to said rotors from the side removed from the face.
- 35 42. A mining machine disposable in inverted positions relative to a mine bottom and comprising a plurality of intermeshing rotors disposed in the same horizontal planes, and means including a plurality of 30 lubricant chambers whereby lubricant may be supplied to said rotors in either inverted position of said machine.
43. A mining machine comprising a frame having a bore, a feed operating member on 45 said frame, and driving mechanism therefor including transmission mechanism including a plurality of intermeshing elements disposed in and removable as a whole longitudinally of said bore.
- 50 44. A mining machine comprising a frame having a bore therein, a feed operating member on said frame, and driving mechanism for said member including transmission mechanism housed in said bore and removable as a whole bodily therefrom, said transmission mechanism including a plurality of intermeshing elements and a driving shaft 55 extending longitudinally of said bore.
- 60 45. A mining machine comprising a frame having a bore therein, a feed operating member on said frame, and driving mechanism for said member including transmission mechanism housed in said bore and removable bodily therefrom, said transmission mecha-
- nism including a plurality of operatively 65 connected internally geared driving mechanisms and cooperating friction clutches.
46. In a mining machine, a frame having a longitudinal bore therein, a feed operating member on said frame, and driving mechanism for the latter including a plurality of ring sections seated in said bore, and transmission mechanism carried by said sections. 70
47. In a mining machine, a frame, a feed operating member thereon, and driving mechanism therefor including a plurality of coaxially disposed internal gears and variable speed transmission mechanism between said gears including another plurality of coaxial internal gears. 75
48. In a mining machine, a frame, a feed operating member thereon, and driving mechanism therefor including a plurality of coaxially disposed internal gears and variable speed transmission mechanism between 80 said gears including another plurality of coaxial internal gears and a plurality of coaxial friction clutches. 85
49. In a mining machine, a frame having a longitudinal bore therein, feed driving 90 mechanism including transmission mechanism in said bore, a member closing one end of said bore, and a feed operating member carried on said closure member and operatively connected to said transmission mechanism. 95
50. In a mining machine, a frame having a feed operating member thereon rotatable on an axis extending longitudinally of the machine, and cooperating guiding mechanism including only a plurality of guiding members disposed on upstanding axes on each side of the axis of said feed operating member, said guiding members at each side of said feed operating member being spaced 100 at materially different distances from the axis of said feed operating member. 105
51. In a mining machine, a frame having a feed operating member thereon rotatable on an axis extending longitudinally of the machine, and cooperating guiding mechanism including only a plurality of guiding members disposed on upstanding axes on each side of the axis of said feed operating member, said guiding members in each set 110 being laterally spaced from one another, said guiding members at each side of said feed operating member being spaced at materially different distances from the axis of said feed operating member. 115
52. In a mining machine, a frame having a feed operating member thereon rotatable on an axis extending longitudinally of the machine, and cooperating guiding mechanism including a plurality of guiding members disposed on upstanding axes on each side of the axis of said feed operating member, said guiding members all being disposed 120
- 125

in a horizontal plane and spaced at materially different distances from the axis of said feed operating member at each side thereof.

53. In a mining machine, a frame, a feed operating member thereon adapted to cooperate directly with flexible feeding means, driving mechanism therefor including fast and slow speed transmission mechanism, and controlling mechanism for the latter including a plurality of friction clutches, and a single control member reversely rotatable on a horizontal axis extending longitudinally of the frame to connect different clutches.

54. In a mining machine, a frame invertible on its top and bottom relative to the mine bottom and slideable over the mine bottom during cutting, cutting and feeding mechanism on opposite ends thereof, driving mechanism therefor therebetween including a motor, and control mechanism for said motor and both of said mechanisms including a plurality of control members on the extremity of the feed end of said machine.

55. In a mining machine, a frame invertible to rest upon its top or bottom relative to the mine bottom and having top and bottom surface providing means constructed to support said machine and to permit sliding thereof with equal facility in either disposition thereof and to enable the machine to cut in different planes, cutting and feeding mechanism on opposite ends thereof, driving mechanism therefor therebetween including a motor, and control mechanism for said machine arranged on said frame wholly between the top and bottom surfaces thereof.

56. In a mining machine, a frame invertible to rest upon its top or bottom relative to the mine bottom and having top and bottom surface providing means constructed to support said machine and to permit sliding thereof with equal facility in either disposition thereof and to enable the machine to cut in different planes, cutting and feeding mechanism on opposite ends thereof, driving mechanism therefor therebetween including a motor, and control mechanism for said machine arranged on said frame wholly between the top and bottom surfaces thereof and including controlling mechanism arranged at the feeding mechanism end thereof.

57. In a mining machine, a frame invertible to rest upon its top or bottom relative to the mine bottom and having top and bottom surface providing means constructed to support said machine and to permit sliding thereof with equal facility in either disposition thereof and to enable the machine to cut in different planes, cutting and feeding mechanism on opposite ends thereof, driving mechanism therefor therebetween including a motor, and control mechanism for

said machine arranged on said frame wholly between the top and bottom surfaces thereof and including controlling mechanism at one end and at one side thereof.

58. In a mining machine, a frame invertible to rest upon its top or bottom relative to the mine bottom and having top and bottom surface providing means constructed to support said machine and to permit sliding thereof with equal facility in either disposition thereof and to enable the machine to cut in different planes, cutting and feeding mechanism on opposite ends thereof, driving mechanism therefor therebetween including a motor, and control mechanism for said machine arranged on said frame wholly between the top and bottom surfaces thereof and including controlling mechanism at the side thereof remote from a working face during cutting.

59. In a mining machine, a frame having a feed operating member thereon rotatable on an axis extending longitudinally of the machine and adapted to cooperate with flexible feeding means, and cooperating guiding mechanism including a plurality of guiding members disposed on upstanding axes on each side of said feed operating member and spaced at materially different distances from the axis of said feed operating member and, said guiding members at each side of said member all being below a horizontal plane passing through the center of the feed operating member.

60. In a mining machine, a frame having a feed operating member thereon rotatable on an axis extending longitudinally of the machine and adapted to cooperate with flexible feeding means, and cooperating guiding mechanism including only guiding members rotating on upstanding axes, a plurality of said guiding members being disposed side by side on upstanding axes on each side of said feed operating member and spaced at materially different distances from the axis thereof and said guiding members at each side of said member all being substantially to the rear of a vertical plane including the pitch circle of the feed operating member.

61. In a mining machine, a frame having a feed operating member thereon rotatable on an axis extending longitudinally of the machine and adapted to cooperate with flexible feeding means, and cooperating guiding mechanism including only guiding members rotating on upstanding axes a plurality of said guiding members being disposed on upstanding axes on each side of said feed operating member and spaced at materially different distances from the axis thereof and said guiding members at each side of said member all being below a horizontal plane passing through the center of the feed op-

erating member and substantially to the rear of a vertical plane including the pitch circle of the feed operating member.

62. In a mining machine, a frame having a feed operating member thereon rotatable on a horizontal axis extending longitudinally of the machine, and cooperating guiding mechanism including only guide members which rotate on fixed vertical axes, there being a plurality of said guide members at each side of the vertical plane including said longitudinally extending axis and certain of said axes being spaced materially further from said plane than others of said axes.

63. In a mining machine, a frame having a bottom engaging portion and a feed operating member thereon rotatable on an axis extending longitudinally of the machine, and cooperating guiding mechanism including only guiding members rotating on upstanding axes a plurality of said guiding members being disposed between a horizontal plane including the axis of said feed operating member and the bottom engaging portion of said frame and rotating on vertical axes and disposed two at each side of the longitudinal vertical plane including the axis of the feed operating member, said guide members at each side of said feed operating member being disposed in the same vertical plane extending transversely of the machine.

64. In a mining machine, a frame having a feed operating member thereon rotatable on an axis extending longitudinally of the machine, and cooperating guiding mechanism including four guiding members disposed on upstanding axes in the same transverse vertical plane and arranged with their pitch circles tangent to a plane including the pitch circle of the feed operating member.

65. In a mining machine, a frame having a feed operating member thereon rotatable on an axis extending longitudinally of the machine, and cooperating guiding mechanism including four guiding members disposed on upstanding axes in the same transverse vertical plane and so disposed that a plane including their pitch circles is tangent to the pitch circle of said feed operating member.

66. In a mining machine, a frame, a feed operating member rotatable thereon on a horizontal axis extending longitudinally of the machine, and driving mechanism therefor including a motor driven pinion coaxial with said feed operating member, a shaft coaxial with said feed operating member and arranged between the same and said motor driven pinion, and transmission mechanism driven by said pinion operative to effect rotation of said feed operating member in opposite directions with said motor driv-

en pinion rotating in the same direction including a plurality of gear elements concentric with said shaft.

67. In a mining machine, a frame, a feed operating member adapted to cooperate directly with flexible feeding means rotatable thereon on a horizontal axis extending longitudinally of the machine, and driving mechanism therefor including a motor driven pinion coaxial with said feed operating member, a shaft coaxial with said feed operating member and arranged between the same and said motor driven pinion, and transmission mechanism driven by said pinion operative to effect rotation of said feed operating member in opposite directions with said motor driven pinion rotating in the same direction including a plurality of gear elements concentric with said shaft, and a plurality of cooperating gear elements rotating on axes parallel to the axis of said shaft.

68. In a mining machine, a frame, a feed operating member adapted to cooperate directly with flexible feeding means rotatable thereon on a horizontal axis extending longitudinally of the machine, and driving mechanism therefor including a motor driven pinion coaxial with said feed operating member, a shaft coaxial with said feed operating member and arranged between the same and said motor driven pinion, and transmission mechanism operative to effect rotation of said feed operating member in opposite directions with said motor driven pinion rotating in the same direction including a plurality of internal gear elements concentric with said shaft.

69. In a mining machine, a frame, a feed operating member adapted to cooperate directly with flexible feeding means rotatable thereon on a horizontal axis extending longitudinally of the machine, and driving mechanism therefor including a motor driven pinion coaxial with said feed operating member, a shaft coaxial with said feed operating member and arranged between the same and said motor driven pinion, and transmission mechanism operative to effect rotation of said feed operating member in opposite directions with said motor driven pinion rotating in the same direction including a plurality of internal gear elements concentric with said shaft and a plurality of spur pinions rotating on axes parallel to the axis of said shaft.

70. In a mining machine, a frame, a feed operating member adapted to cooperate directly with flexible feeding means rotatable thereon on a horizontal axis extending longitudinally of the machine, and driving mechanism therefor including a motor driven pinion coaxial with said feed operating member, a shaft coaxial with said feed operating member and arranged between the same and said motor driven pinion, and transmission mechanism driven by said pinion operative to effect rotation of said feed operating member in opposite directions with said motor driv-

same and said motor driven pinion, and transmission mechanism operative to effect rotation of said feed operating member in opposite directions with said motor driven pinion rotating in the same direction including a plurality of internal gear elements and spur gear elements all coaxial with said shaft.

71. In a mining machine, a frame, a feed operating member adapted to cooperate directly with flexible feeding means rotatable thereon on a horizontal axis extending longitudinally of the machine, and driving mechanism therefor including a motor driven pinion coaxial with said feed operating member, a shaft coaxial with said feed operating member and arranged between the same and said motor driven pinion, and transmission mechanism operative to effect rotation of said feed operating member in opposite directions with said motor driven pinion rotating in the same direction including a plurality of internal gear elements and spur gear elements all coaxial with said shaft and a plurality of cooperating gear elements rotating on parallel axes.

72. A mining machine having cutting mechanism and a bottom plate underlying the same on which the machine is slidably supported and a cover plate overlying the same, a cutter chain driving sprocket between said plates, and a member of a length substantially equal to the height of the machine extending axially through said sprocket binding together said plates, said cover plate forming the topmost surface of the machine.

73. A mining machine having cutting mechanism and a bottom plate underlying the same on which the machine is slidably supported and a cover plate overlying the same, said cover plate forming the topmost surface of the machine, a cutter chain driving sprocket and a coaxial driving gear therefor both between said plates, and a member of a length substantially equal to the height of the machine extending axially through said members binding together said plates.

74. A mining machine having cutting mechanism and a frame presenting parallel plane top and bottom surfaces and including a bottom plate underlying said cutting mechanism and on which the machine is slidably supported and a cover plate overlying the same, a cutter chain driving sprocket between said plates, and means extending axially through said sprocket including a stationary member binding together said plates, said member extending substantially through said frame to points closely adjacent the top and bottom surfaces thereof.

75. A mining machine having cutting mechanism and a frame presenting parallel plane top and bottom surfaces and includ-

ing a bottom plate underlying said cutting mechanism and on which the machine is slidably supported and a cover plate overlying the same, a cutter chain driving sprocket and a coaxial driving gear therefor both between said plates, a member extending axially through said members binding together said plates, and means maintaining said sprocket and driving member in predetermined longitudinal positions relative to one another, said binding member extending substantially through the frame to points closely adjacent the top and bottom surfaces thereof.

76. Mining machine cutting mechanism comprising a bevel pinion rotatable on a horizontal axis, a horizontal bevel gear meshing therewith, a spur pinion above and coaxial with said bevel gear, a larger spur gear meshing with said pinion, and a cutter chain driving sprocket below and rotatable with said larger gear disposed in substantially the same horizontal plane with said bevel pinion.

77. Mining machine cutting mechanism comprising a bevel pinion rotatable on a horizontal axis, a horizontal bevel gear meshing therewith, a spur pinion above and coaxial with said bevel gear, a larger spur gear meshing with said pinion, and a cutter chain driving sprocket below and rotatable with said larger gear disposed in substantially the same horizontal plane with said bevel pinion and having its bearing projecting upwardly.

78. Mining machine cutting mechanism comprising a bevel pinion rotatable on a horizontal axis, a horizontal bevel gear meshing therewith, a spur pinion above and coaxial with said bevel gear, a larger spur gear meshing with said pinion, and a cutter chain driving sprocket below and rotatable with said larger gear disposed in substantially the same horizontal plane with said bevel pinion and having bearings located above and below said sprocket.

79. An invertible mining machine frame carrying cutting and feeding mechanism and slidably directly on the mine bottom selectively on opposite surfaces of said frame under the propulsion of said feeding mechanism and having means for lubricating said feeding mechanism operative in either position of said frame.

80. A mining machine comprising an invertible frame including a motor and feeding mechanism driven thereby and slidably directly on the mine bottom under the propulsion of said feeding mechanism when said frame is disposed selectively on opposite surfaces thereof and means for lubricating said motor and feeding mechanism operative in either position of said frame.

81. An invertible mining machine frame carrying cutting and feeding mechanism and

slidable on the mine bottom selectively on opposite surfaces of said frame to enable the machine to cut in different planes and having means for permitting removal of said feeding mechanism in either position of said frame.

82. A mining machine frame carrying cutting and feeding mechanism and slidable on the mine bottom on opposite surfaces of said frame and having means for permitting removal of said feeding mechanism longitudinally through one end of said frame in either position of said frame.

83. An invertible mining machine frame carrying cutting and feeding mechanism and slidable on the mine bottom selectively on opposite surfaces of said frame to enable the machine to cut in different planes, and means for permitting removal of said cutting mechanism in either position of said frame.

84. An invertible mining machine frame carrying cutting and feeding mechanism and slidable on the mine bottom selectively on opposite surfaces of said frame to enable the machine to cut in different planes, and means for permitting removal of said feeding mechanism and said cutting mechanism in either position of the frame.

85. A mining machine carrying cutting and feeding mechanism and presenting an invertible frame having substantially plane top and bottom surfaces on either of which it is slidable on a mine bottom to enable the machine to cut in different planes, said frame having substantially plane sides either of which is disposable close to a mine face during cutting, and controlling mechanism for said mechanisms disposed substantially within the cross sectional limits of said frame.

86. In a mining apparatus, a machine frame having opposed surfaces each adapted to support the frame for sliding over the mine bottom during cutting, cutting mechanism carried by said frame at one end of the latter, feeding mechanism carried by said frame at the other end thereof, and a driving motor for said mechanism arranged symmetrically with said frame both laterally and vertically.

87. In a mining apparatus, a machine frame having opposed surfaces adapted to support the machine for sliding upon a mine bottom during cutting, cutting mechanism carried by said frame, a motor carried by said frame, and feed gearing on said frame at the opposite end of the latter from said cutting mechanism, said feed gearing having a primary axis between the top and bottom and midway between the sides of the frame.

88. In a mining apparatus, a machine frame having opposed surfaces adapted to support the machine for sliding upon a mine

bottom during cutting, cutting mechanism carried by said frame, a motor carried by said frame, and feed gearing on said frame at the opposite end of the latter from said cutting mechanism, said feed gearing having a primary axis between the top and bottom and midway between the sides of the frame, and said motor being symmetrically arranged with respect to said frame both laterally and vertically.

89. In a mining apparatus, a machine frame comprising a motor having a casing slidable directly on the mine bottom and which determines the height of the mining machine, cutting mechanism at one end of said frame, and feeding mechanism at the other end of said frame including a feed operating member rotating on an axis extending longitudinally of said frame.

90. A mining machine having an invertible machine frame slidable on the mine bottom and presenting spaced parallel surfaces on which the machine is adapted to be selectively supported, cutting mechanism carried by said frame between the surfaces thereof including a power driven gear, a coaxially disposed cutter chain driving sprocket rotatable therewith, a coaxially disposed stud extending through each of the same, and anti-friction bearings between said gear and stud and said sprocket and stud and spaced longitudinally of the latter, one of said bearings receiving the axial thrust of said sprocket when said frame is supported on one surface thereof while another bearing receives the axial thrust of said sprocket when said frame is inverted and supported on its other surface.

91. A mining machine cutting mechanism including a power driven gear, a coaxially disposed cutter chain driving sprocket rotatable therewith, a coaxially disposed stud extending through each of the same, said stud having a flange on the periphery thereof intermediate its ends, and anti-friction bearings between said gear and stud and said sprocket and stud and spaced longitudinally of the latter, one of said bearings receiving the axial thrust of said sprocket in one direction and engaging said flange.

92. A mining machine cutting mechanism including a power driven gear, a coaxially disposed cutter chain sprocket rotatable therewith, said elements having hub portions and being releasably connected together and said gear being axially removable relative to said sprocket, and a journal sleeve enclosing said hubs and removable axially upon axial removal of said gear.

93. A cutting mechanism for mining machines including an axially removable gear, a coaxial stud having a flange on the periphery thereof intermediate its ends, a coaxial cutter chain sprocket rotatable with said gear, bearings disposed coaxially with

- said stud, one of said bearings receiving the axial thrust of said sprocket in one direction and engaging said flange, and a coaxial cup bearing for said sprocket, another of said 5 bearings receiving the axial thrust of said sprocket in the opposite direction and engaging said cup bearing.
94. An invertible mining machine cutting mechanism including a power driven gear, 10 a coaxially disposed cutter chain driving sprocket rotatable therewith, a coaxially disposed stud extending through each of the same and having a flange on the periphery thereof intermediate its ends, and anti-friction 15 bearings between said gear and stud and said sprocket and stud and spaced longitudinally of the latter, said flange receiving the axial thrust of different bearings 20 when said cutting mechanism is disposed in its different inverted positions.
95. In a mining machine, a frame having a feed operating member thereon rotatable on an axis extending longitudinally of the machine and adapted to cooperate directly 25 with flexible feeding means, and cooperating guiding mechanism including a plurality of guiding members disposed on vertical axes on each side of the axes of said feed operating member, the axes of the guiding 30 members at each side of said feed operating member being parallel and disposed in the same vertical transverse plane.
96. In a mining machine, a frame, cutting mechanism including a cutter bar pivotally mounted on one end of said frame, and feeding mechanism including a feed operating member on the opposite end of said frame and rotatable on an axis extending longitudinally of the machine and flexible feeding 35 means cooperating therewith, and cooperating guiding mechanism including a plurality of guiding members disposed on vertical axes in the same transverse plane at each side of the axis of said feed operating 40 member, said flexible feeding means being adapted to be extended from said feed operating member around certain of said guiding members to effect bar swing and around others of said members to effect feed of the 45 machine relative to the coal face during cutting.
97. A mining machine cutting mechanism including a power driven gear, a coaxially disposed cutter chain driving sprocket rotatable therewith, a coaxially disposed stud 50 extending through each of the same, anti-
- friction bearings between said gear and stud and said sprocket and stud spaced longitudinally of the latter, and a cutter bar pivotally supported coaxially with said stud, 60 said cutter bar support including journals disposed above and below said sprocket.
98. A mining machine having a single swingable cutter chain carrying cutter bar and flexible feeding means, and bar locking 65 means to lock said bar when the latter is swung into its different angular positions, said flexible means being connectible with said locking means to effect bar swing and including means for preventing contact between 70 said flexible means and said cutter chain when slack enters said flexible means while the latter extends above and across the path of said cutter chain.
99. A mining machine having a single 75 swingable cutter chain carrying cutter bar and flexible feeding means, and bar locking means movable with said bar to lock said bar when the latter is swung into its different angular positions, said flexible means 80 being connectible with said locking means to effect bar swing and including means for preventing contact between said flexible means and said cutter chain when slack enters 85 said flexible means while the latter extends above and across the path of said cutter chain.
100. In a mining apparatus, a machine frame having opposed surfaces adapted to support the machine for sliding upon a mine 90 bottom during cutting, cutting mechanism carried by said frame, a motor carried by said frame, and feeding mechanism including a feed operating member on said frame at the opposite end of the latter from said 95 cutting mechanism, said feed operating member having its axis horizontal and disposed midway between the top and bottom of said frame.
101. In a mining apparatus, a machine 100 frame comprising a motor having a casing slidable directly on the mine bottom and which determines the height of the mining machine, cutting mechanism at one end of said frame, and feeding mechanism at the 105 other end of said frame including a feed operating member rotatable on a horizontal axis midway between the top and bottom of said motor casing.

In testimony whereof I affix my signature.

MORRIS P. HOLMES.

.7

CERTIFICATE OF CORRECTION.

Patent No. 1,670,155.

Granted May 15, 1928, to

MORRIS P. HOLMES.

It is hereby certified that error appears in the printed specification of the above numbered patent requiring correction as follows: Page 2, line 77, for the word "to" first occurrence read "at"; page 4, line 14, after the word "face" strike out the comma and insert a period; page 9, line 24, for the word "jacket" read "jack"; page 11, line 118, claim 23, for the word "car" read "bar"; page 14, line 101, claim 60, for the misspelled word "exis" read "axis"; same page, line 121, claim 61, and page 15, line 22, claim 63, after "axes" insert a comma; page 18, line 28, claim 95, for "axes" second occurrence read "axis"; and that the said Letters Patent should be read with these corrections therein that the same may conform to the record of the case in the Patent Office.

Signed and sealed this 10th day of July, A. D. 1928.

(Seal)

**M. J. Moore,
Acting Commissioner of Patents.**
